UNITED STATES PATENT OFFICE

LE ROY W. FAIRCHILD, OF NEW YORK, N. Y.

DESIGN FOR PENCIL-CASES.

Specification forming part of Design No. **11,433**, dated September 23, 1879; application filed August 16, 1879.
[Term of patent 7 years.]

To all whom it may concern:

Be it known that I, LE ROY W. FAIRCHILD, of the city, county, and State of New York, have produced a new and original Design for an Ornamental Pencil or Small-Implement Case, of which the following is a full, clear, and exact description, reference being had to the accompanying photographic illustration, making part of this specification.

The design consists in forming upon the outer tube or shell of a small-implement case—such as a pencil, tooth-pick, or the like—the figure of a bear in the attitude of climbing.

A represents the ornamental case entire. b

is a ring, said ring being loosely confined to the solid or closed end of the case by the eye c. d is the figure of the bear, affixed to the case proper at or about midway between the two ornamental beads e and f.

What I claim as my invention is—

A design for a case for small implements, consisting of the tubular shell, the figure of a bear, d, ring b, eye c, and beads e and f, substantially as shown and described.

LE ROY W. FAIRCHILD.
